(57) **CLAIM**

The ornamental design for a wearable exercise analysis device, as shown and described.

DESCRIPTION

FIG. 1 is a front perspective view of a wearable exercise analysis device, showing our new design;

FIG. 2 is a front perspective view thereof, showing an alternative configuration;

FIG. 3 is a rear perspective view thereof, showing the alternative configuration;

FIG. 4 is a rear elevational view thereof;

FIG. 5 is a front elevational view thereof;

FIG. 6 is a bottom plan view thereof;

FIG. 7 is a bottom plan view thereof, showing the alternative configuration;

FIG. 8 is a left elevational view thereof;

FIG. 9 is a right elevational view thereof;

FIG. 10 is a top plan view thereof; and,

FIG. 11 is a top plan view thereof, showing the alternative configuration.
